UNITED STATES PATENT OFFICE

90,738

DESIGN FOR A MOTORIST POCKET POUCH

William Roscoe Tatum, Percy, Ill.

Application May 4, 1931. Serial No. 39,714

Term of patent 3½ years

To all whom it may concern:

Be it known that I, WILLIAM ROSCOE TATUM, a citizen of the United States, residing at Percy, in the county of Randolph and State of Illinois, have invented a new, original, and ornamental Design for a Motorist Pocket Pouch, of which the following is a specification, reference being had to the accompanying drawing, forming part thereof.

Fig. 2 is a rear elevation thereof.

I claim:

The ornamental design for a motorist pocket pouch, as shown.

WILLIAM ROSCOE TATUM.
